FLUID FUEL FLOW CONTROL FOR GAS BURNING TOP BURNER

Domenick Saponara, Allentown, Pa., assignor to Caloric Corporation, Philadelphia, Pa., a corporation of Pennsylvania
Continuation of application Ser. No. 602,285, Dec. 16, 1966. This application May 27, 1968, Ser. No. 740,774
Int. Cl. F23d 13/02; F23n 5/02, 1/00

2 Claims

ABSTRACT OF THE DISCLOSURE

A thermostatically controlled valve for enabling an automatic top burner to operate at an extremely low B.t.u. in-put without any risk of extinguishing the flame.

This application is a continuation of Ser. No. 602,285, filed Dec. 16, 1966, now abandoned.

Background

Is that of a gas burning stove wherein flow of gas to the top burners is automatically increased, or decreased, or temporarily shut off altogether, in response to the temperature of the utensil which contains the food to be cooked. Moderate down-throttling, that is, non-radical reduction of the flow of gas poses no problem because the velocity of the gas entering the venturi of the burner remains high enough to entrain the required air, and the flame, although reduced, remains hard and stable. But reduction of the gas input to a value of the order of 500 B.t.u. which produces the desired low temperature produces an unstable flame which may be extinguished by slight atmospheric disturbances. This is due to the fact that, when the gas flow is reduced to about 500 B.t.u. per hour, the pressure under which gas is delivered to the burner venturi drops from about 4 inches of water which is the average normal pressure in the gas main, to about .04". At this pressure, the gas velocity is so low that it cannot entrain the required combustion air and the flame may be extinguished. It is in recognition of this danger that the American Gas Association has ruled that the smallest flame of an automatic burner must be able to withstand a three-mile-an-hour air current. To limit the down-throttling to insure a hard and stable flame, is to limit the benefits which the cycling is intended to vouchsafe.

The prior art

As far as I am aware, the prior art has proposed the use of an auxiliary "spot" burner which was located adjacent the main burner and was supplied with gas at reduced volume but at substantially the pressure of about 4 inches which prevails in the gas main. This arrangement produced a hard and stable flame, but it also involved the cost of the additional burner and piping. Furthermore, a "spot" burner acted on a small area of the bottom of the cooking utensil instead of diffusing the heat over the entire area thereof.

The invention

Resides in providing means for reducing the volume of gas delivered to the burner to about 500 B.t.u. per hour without materially reducing the pressure and velocity at which the gas is delivered.

The drawings

In the drawings, FIG. 1 is a vertical, sectional view of a thermostatically-controlled valve embodying this invention, the valve being adapted for use in the "by-pass" type of burner, and being shown in full open position.

2

FIG. 2 is similar to FIG. 1 but shows the valve in full, closed position.

FIG. 3 is similar to FIG. 1, and shows the valve adapted for converting a "tower" type of burner to the "by-pass" type.

Description of a conventional "by-pass" type valve

A conventional "by-pass" type valve includes a casing 14 which is internally divided to form compartments 12, 16, and 32, and is provided with a conventional disc valve 18 which controls the flow of gas from compartment 12 to compartment 16, and with orifice 22 which is adjusted by screw 23 for controlling the flow of gas from compartment 16 to compartment 32, and with valve 36 which controls passage 30 to regulate the flow of gas from compartment 16 to compartment 32. Compartment 32 has an orifice 34 which discharges the gas into end 44 of a conventional venturi which leads to burner 20. Valve 36 is pivotally mounted on one end of arm 38, the other end of which is hinged to the bottom wall of casing 14. Arm 38 is moved to the left, or right, as viewed in FIG. 1 by the expansion, or contraction, of a bellows 40 in response to the expansion and contraction of a fluid in a conventional sensing device 42, which has following contact with the bottom of the utensil and which is connected to the bellows by tube 43. Compartment 12 receives gas directly from gas main 10 at the normal pressure of about 4 inches of water.

Description of the operation of a conventional "by-pass" valve

A conventional valve of the type described, operates as follows. The main valve 18 is opened to admit gas from the main 10 to compartment 12 and a conventional thermostat, not shown, is set to the temperature it is desired to maintain. As the temperature rises, valve 36 progressively throttles down passage 30, and vice versa. It will be appreciated that, as long as valve 36 is open enough to maintain a substantial flame, there is no problem. But, when passage 30 is completely closed, the burner will be supplied by orifice 22 only and the small amount of gas entering chamber 32 undergoes a reduction in pressure from about 4 inches to a fraction of one inch. The velocity of gas entering the venturi will also be so reduced that insufficient combustion air is entrained and the burner flame will be weak and subject to extinguishment.

Description of one preferred embodiment

To overcome the difficulties set forth, I provide fitting 24, one end of which is enlarged to form a plenum 25 which receives gas from orifice 22 and the other end of which is in the form of a narrow tube 26 which terminates immediately adjacent discharge orifice 34. In other respects, the valve structure may be as shown in FIG. 1.

Operation of the said one preferred embodiment

Once screw 23 has been set, it is left undisturbed, and gas will flow into compartment 32 through orifice 27 and through opening 30. It will be noted that with valve 18 open, the pressure in plenum 25 will be about the same as in main 10 and that restriction tube 26, if anything, increases the velocity of the gas flowing therethrough, so that the gas flowing from orifice 27 will flow out of orifice 34 and into the burner venturi at a velocity sufficient to entrain the combustion air needed to produce a stable flame which can withstand the three-miles-an-hour wind test.

Description of a conventional tower type burner

A "tower" type burner includes a spot burner, not shown, which is located adjacent burner 20, and is con-

nected to compartment 16 by tube 43' so as to be supplied with full pressure gas at all times.

Description of a second preferred embodiment

According to my invention, I eliminate the spot burner and I introduce one end of a tube 46 into compartment 16' with the end 27' thereof, adjacent orifice 34'. By this arrangement, tube 46 discharges gas into orifice 34' at substantially gas main pressure in the same manner as the gas is discharged through orifice 27 in the embodiment of FIG. 1.

A working prototype was built and proved to be entirely successful in that the flame withstood the three-miles-an-hour test even when the gas input was reduced to about 500 B.t.u. per hour.

What is claimed is:

1. A valve mechanism for controlling the flow of gas to a burner, said mechanism including:
  - a casing,
  - means dividing the interior of said casing to form a first compartment and a second compartment,
  - supply means for supplying said first compartment with said gas at a pre-determined pressure and in a relatively large volume,
  - a thermostatically controlled valve having a passage for passing said gas in variable volume from said first to said second compartment,
  - the volumetric capacity of said second compartment being so related to the flow capacity of said passage that restriction of said passage causes a corresponding reduction in the gas pressure in said second compartment,
  - said second compartment having an end member provided with a discharge orifice for delivering said gas from the second compartment to the burner, and

a wholly separate and independently adjustable auxiliary supply means located within said casing for delivering said gas in a fixed, greatly reduced volume from said first compartment through said orifice, said auxiliary supply means comprising an elongated conduit having a first end terminating in coaxial alignment with said discharge orifice, the opposite end of the conduit communicating with said first compartment, the conduit providing means for delivering said gas through the discharge orifice from the first compartment at increased velocity and without interference, said first end of the conduit being spaced slightly inwardly from said end member of the second compartment and from said discharge orifice to permit discharge of gas introduced into the second compartment via said valve.

2. A valve mechanism as set forth in claim 1 having a nonthermostatically controlled valve between said first compartment and said conduit for controlling the flow of gas to said conduit.
